United States Patent

Des. 234,548

Patented Mar. 18, 1975

234,548

KEY HOLDER

Alwin J. Stahel, New Brighton, Minn., assignor to
Teraco, Inc., Midland, Tex.

Filed May 21, 1973, Ser. No. 362,188

Term of patent 14 years

Int. Cl. D3—99

U.S. Cl. D87—8

FIG. 1

FIG. 2

FIG. 3

FIG. 4

FIG. 5

FIG. 1 is a top perspective view of a key holder showing my new design;

FIG. 2 is a top plan view thereof with the loop and ring portions omitted;

FIG. 3 is a side elevational view thereof, the opposite side being a mirror image thereof;

FIG. 4 is an end view taken from the right end of FIG. 3; and

FIG. 5 is a bottom plan view.

I claim:

The ornamental design for a key holder, substantially as shown and described.
